J. D. KARLE.
BOBBIN WINDING ATTACHMENT.
APPLICATION FILED MAY 2, 1918.

1,290,225.

Patented Jan. 7, 1919.

UNITED STATES PATENT OFFICE.

JOHN D. KARLE, OF ROSELLE PARK, NEW JERSEY, ASSIGNOR TO THE SINGER MANUFACTURING COMPANY, A CORPORATION OF NEW JERSEY.

BOBBIN-WINDING ATTACHMENT.

1,290,225.

Specification of Letters Patent.

Patented Jan. 7, 1919.

Application filed May 2, 1918. Serial No. 231,988.

To all whom it may concern:

Be it known that I, JOHN D. KARLE, a citizen of the United States, residing at Roselle Park, in the county of Union and 5 State of New Jersey, have invented certain new and useful Improvements in Bobbin-Winding Attachments, of which the following is a specification, reference being had therein to the accompanying drawings.

10 This invention relates to attachments for sewing machines for winding thread on bobbins which, as is well known, carry the under thread of lock-stitch machines.

15 The present invention is an improvement 15 of the construction disclosed in the prior patents to Eames & Finch No. 809,911, of Jan. 9, 1906 and Karle No. 1,014,483, of Jan. 9, 1912. It aims to cheapen the cost of manufacture of the type of bobbin-winder 20 shown in these patents and to better their operation by relieving the operator of the necessity of guiding the thread while it is being wound, thereby conserving her time and energy.

25 It consists of a sheet-metal base-plate having ears struck up at one end thereof on which ears the bobbin winding mechanism is operatively supported adjacent a belt driving the sewing machine and of a thread- 30 guide formed in an angle-plate which is adjustably secured at the opposite end of the base-plate at such a distance from the bobbin-winding mechanism that the thread being wound can distribute itself uniformly 35 over the bobbin being filled.

The invention is illustrated in the accompanying drawings, in which Figure 1 is a plan view and Figs. 2 and 3 are side and end elevations, respectively, thereof. Fig. 40 4 is a vertical section through the bobbin-winding mechanism and Fig. 5 is a plan view of one end of the sheet-metal base in its blank form.

An elongated sheet-metal base 1 is 45 stamped out to form ears 2, 3, 3' and 4, the form of the blank being illustrated in Fig. 5. The first three of the ears mentioned are subsequently bent up at substantially right angles to the body of the base. 50 Hinged to and between the ears 3-3' is a standard or frame 5 carrying a shaft 6, pulley 7 and holder 8, and connecting the ear 2 with an arm 9 of the standard or frame 5 are the toggle links 10 and 11, the latter 55 of which carries a trip-finger 12. The parts

are constructed and operated substantially as disclosed in the above mentioned patents and no extended description is therefore necessary.

In the standard or frame 5 a socket 13 is 60 provided to receive the spring 14 which thrusts a plunger 15 against the ear 4 of the base-plate and tends to hold the frame or standard either in a raised position with its pulley 7 tracking a belt (not shown) of 65 a sewing machine or in a lower position out of engagement with the belt and against the brake-pin 16 suitably secured in the sheet-metal base 1. The action results from the disposition and arrangement of the toggle 70 links 10-11 relative to the standard or frame 5 as will be readily understood by reference to the prior patents mentioned above.

Disposed at the end of the base 1 opposite 75 to that on which the bobbin-winding mechanism is arranged is a sheet-metal plate 17 of angular form pierced to form a thread-guiding eye 18 adjacent which a constant tension device 19 of any suitable form is 80 secured. In the plate 17 a slot 20 is provided to receive the clamping screw 21 which is threaded into the base 1 which base in turn is slotted at 22 to receive a blind rivet 23 stamped downwardly from the plate 85 17. The screw 21 and the slot 22 are arranged preferably in a line parallel to the axis of the shaft 6 and these expedients permit of adjusting the angle-plate 17 transversely of the base 1 and positioning the 90 thread-guide 18 in perpendicular bisecting relation with the axis of the bobbin which is indicated at 24. The base 1 is preferably bent as indicated at 25 to conform to the trough commonly provided in power-tables 95 in general use. Slots 26 are also provided in the base 1 for mounting the attachment conveniently and securely in juxtaposition to the driving belt of a sewing machine.

The thread of course passes from a source 100 of supply to the constant tension 19, thence through the eye 18 to and around the bobbin 24 which is adapted to be rotated at the pleasure of the operative by straightening out the toggle links 10-11 so that they assume the position shown in Fig. 2 with the pulley 7 in contact with a belt driving the sewing machine at which the operator is working. When the bobbin is filled the trip-finger 12 throws the knuckle-joint of 110

the toggle across and to the opposite side of a line connecting the outer end pivots of the links 10—11, thereby permitting the spring-pressed plunger-pin 15 to swing the standard or frame 5 out of contact with the belt driving it and against the brake-pin 16 which quickly arrests rotation of the bobbin.

The construction described is easily and 10 cheaply produced in quantity. The distance between the thread-guide 18 and bobbin 24 permits the thread to distribute itself uniformly across the width of the bobbin without any attention or care from the operator. The common base supporting both the 15 guide and bobbin winding mechanism insures reliability in self distribution of the thread not attained in any prior attachment of this same type and simplifies the setting 20 up of power-tables to which it is especially suited.

Having thus set forth the nature of the invention, what I claim herein is:—

1. In a bobbin-winding attachment for 25 belt driven sewing machines; in combination, a sheet-metal base-plate of elongated form, a plurality of ears struck up from said sheet-metal base-plate at one end thereof, a rotatable bobbin-winding mechanism 30 pivotally connected and supported by said ears, a sheet-metal plate having a thread guiding aperture therein and secured to the other end of said base-plate with the aper-

ture at a relatively great distance from the bobbin-winding mechanism, whereby thread 35 being wound on a bobbin is self distributed.

2. In a bobbin-winding attachment for 40 belt driven sewing machines, in combination, a sheet-metal base-plate having a plurality of ears in one piece therewith, and a 45 rotatable bobbin-winding mechanism operatively supported by said ears and including a swinging standard having a spring-pressed plunger socketed therein, the plunger being adapted to thrust against said sheet-metal base-plate.

3. In a bobbin-winding attachment for 50 belt driven sewing machines, in combination, a sheet-metal base-plate of elongated form, a plurality of ears struck up from 55 said sheet-metal base-plate at one end thereof, a rotatable bobbin-winding mechanism pivotally connected and supported by said ears, a sheet-metal plate of angular form secured to the other end of said base-plate and having a thread-guiding aperture therein, a tension device secured to said sheet-metal plate adjacent said thread-guiding aperture, said sheet-metal plate being adjustable transversely of the base-plate in 60 order to locate said thread-guiding aperture in perpendicular bisecting relation to the axis of the bobbin being wound.

In testimony whereof, I have signed my name to this specification.

JOHN D. KARLE.
